UNITED STATES PATENT OFFICE

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

CRACKING BITUMINOUS MATERIAL

Application filed December 30, 1925. Serial No. 78,294.

This invention relates to improvements in process of cracking bituminous material, and in the present application the invention is more particularly directed to destructively 5 distill such more or less solid bituminous materials such as coal, tars, shales and such natural asphaltic materials as for example gilsonite, Trinidad, grahamite and the like.

In the present invention, this destructive 10 distillation of such bituminous materials may be carried out by subjecting such materials to the action of heated petroleum oil.

This highly heated petroleum oil, serves in part to dissolve out of the bitumen, the hydrocarbonaceous material, also to vaporize 15 such material and crack it.

In carrying out the invention, to accomplish the above mentioned objects, I first 20 preferably pass petroleum oil through a heating furnace where it is subjected to cracking conditions of temperature and pressure, and while the oil is in such condition, deliver it to a suitable chamber containing the solid or semi-solid bituminous material. 25 From this chamber both the vapors from the petroleum oil and vapors from the bituminous material pass out where they are subjected to suitable condensing action.

The invention will be more readily understood 30 from the following description in which the single figure in the accompanying drawing, shows a diagrammatic view, partly in side elevation and partly in vertical section of an apparatus suitable for carrying 35 out the present invention.

Referring to the drawing, 1 designates the furnace in which is mounted a heating coil 2. The oil is delivered to the heating coil through the feed line 3 provided with 40 the pump 4 connected to any suitable source of charging stock, not shown. The petroleum oil passes from the heating coil 2 into one or the other of the expansion chambers 5 and 6. Expansion chamber 5 is connected 45 by transfer line 7 having throttle valve 8 to the heating coil 2 while the chamber 6 is connected by transfer line 9 having throttle valve 10 to the delivery end of the coil 2 in the same manner.

50 I have shown in the present instance only

two of these chambers 5 and 6, but any suitable number may be connected to the coil if desired, and they may be used alternately, or connected in multiple as for example in pairs, and run simultaneously.

55

These chambers may also be preferably insulated if desired, and may be externally heated. Each of the chambers 5 is provided with a residuum drawoff 10' having a throttle valve 11, and with suitable manholes 12 and 13. The vapors pass out of the upper portions of the chambers 5 and 6 through the lines 14 controlled by throttle valves 15 into the lower portion of the dephlegmator or reflux condenser 16. The reflux condensate 60 is drawn off from the bottom of the dephlegmator through the pipe 17, and is preferably forced by pump 18 into the feed line 3. If desired, the reflux condensate may be diverted elsewhere through the line 19 by suitably 65 controlling the valves 20 and 21. The vapors pass out through the top of the dephlegmator to pipe 22 controlled by valve 23, thence to water condenser 24, thence to receiver 25, suitable throttle valves 26, 27 and 28 being 70 connected with the receiver as shown.

If desired, a fixed or incondensable gas such as a hydrogen containing gas from the receiver 25, or other hydrocarbon gases may be introduced through a suitable source of 75 supply by means of gas pump 29 either to the feed line 3 through pipe 30 controlled by throttle valve 31, or to the lower portion of the expansion chambers through pipes 32 controlled by suitable throttle valves 33, or if 80 desired, the gas may be introduced simultaneously into both the chambers and the heating coil.

The object of introducing this incondensable gas is not only to facilitate vaporization, 85 but also to cause more or less hydrogenation.

The process may be carried out as follows:

I may charge either one or both of the chambers 5 and 6 with bituminous material such as bituminous coal in a more or less divided condition so that it may be readily charged into the chambers 5 and 6. It may be desirable in some instances, to heat the coal in the chambers to a temperature of from 800° 90 to 900° F. by means of suitable burners not 100

shown, and then the petroleum oil or fuel oil fed through the heating coil 2 where it may be heated to a transfer temperature of 950° F. more or less, under a pressure of 500 pounds. This hot oil is then delivered to one or more of the expansion chambers where of course, more vaporization will take place. The hot oil and hot vapors in the chambers 5 and 6 act on the coal to dissolve or distill out some of the hydrocarbonaceous material, and also to crack some of it, depending upon the cracking conditions of temperature and pressure in such chambers.

10 In carrying out the process in the manner now being described, these chambers may be subjected to a vapor pressure of say 200 pounds or more, with a vapor temperature of say 850° F. in the vapor lines leading to the dephlegmator 16. The temperature of the 15 dephlegmator may be controlled as desired, so as to condense the insufficiently cracked vapors, which may then be drawn off and run again through the coil 2, or treated elsewhere, as desired. The dephlegmator, water condenser and receiver may be under a pressure of 150 pounds. It is understood the temperatures and pressure here given, are merely typical, and other temperatures and pressures may be used, for example, certain of 20 the bituminous materials will distill more readily than others with lower temperatures and lower pressures. The temperature and pressure however, should be such as to distill off a substantial portion of the hydrocarbonaceous material contained in the coal or other bitumen being treated.

25 I claim as my invention :

30 In the art of recovering values from hydrocarbon sources, charging a chamber with hydrocarbon solids capable of destructive distillation, imparting cracking temperature to hydrocarbon liquid, and discharging the heated liquid into the chamber and thereby 35 raising the solids to distillation temperature.

40 45 GUSTAV EGLOFF.
